UNITED STATES PATENT OFFICE.

VICTOR B. PHILLIPS, OF CLEVELAND, OHIO, ASSIGNOR TO BOURN RUBBER MANUFACTURING COMPANY, OF PROVIDENCE, RHODE ISLAND, A CORPORATION OF RHODE ISLAND.

FOOTWEAR.

Application filed January 22, 1927. Serial No. 162,815.

This invention pertains to footwear and more particularly to overshoes, women's gaiters, galoshes or similar articles adapted to be worn over the ordinary shoe to protect the foot and lower part of the leg from wet and cold.

Manufacturers are now making overshoes with permanently attached cuffs to impart an ornamental finish to the top of the overshoe. Sometimes these cuffs are of the same material as the top of the overshoe and sometimes of other materials, for example, plush, fur, etc., but these cuffs constitute a permanent part of the overshoe, and as overshoes are made in a wide range of sizes, it is obvious that the shoe retailer can not be expected to carry overshoes having cuffs of a great many different colors or materials.

Persons who are fastidious in dress wish to have their several articles of apparel in harmonious colors or materials, but owing to the limited stock of overshoe cuffs usually available, it is difficult, and often impossible, to obtain overshoes having cuffs of a suitable color or material to meet the wearer's requirements. In accordance with the present invention, I construct the overshoe, galosh, gaiter, Russian boot or the like in substantially the usual manner, omitting the permanently attached cuff, but I furnish the upper part of the overshoe with one or more fastener elements, for example, snap fasteners, buttons, buttonholes, hooks or eyes. I then furnish each pair of overshoes with one or more pairs of cuffs or cuff foundations, such cuffs or foundations having fastener elements complementary to those carried by the overshoe, thus adapting the cuff or cuff foundation to be attached to or detached from the overshoe at will.

Detached cuffs of this character may readily be made in a great variety of materials and colors since they are much less expensive to manufacture than a complete shoe and especially as they need not necessarily follow size standards so closely as the overshoes. Within the scope of the present invention, I contemplate, as above noted, the manufacture and sale of what I have termed cuff foundations, that is to say, bands or strips of suitable material provided with the proper fastener elements and adapted to be covered in accordance with the desires of the jobber, retailer or user with material or substances adapted to impart the desired

surface appearance and which may match or provide a pleasing contrast to the coat, gown or other garment with which the cuff is to be worn.

Obviously, such cuffs may be made as complete rings if desired, for example, when intended to be worn with a Russian boot, but I contemplate that the more usual form of cuff will consist of a simple elongate strip or band of material having the attached fasteners secured thereto and if desired having additional fastener elements at its ends to permit the ends to be joined to form a complete ring or circle when in use.

When certain materials are employed as the base or supporting element of the cuff, for example, waterproof or other relatively stiff materials, I may provide the cuff with a preformed fold or flap disposed substantially parallel to or at a more or less acute angle to the plane of the main body or cuff, and attach the fastener elements to this fold or flap. This permits the cuff proper to lie smooth and free from wrinkles or puckers while at the same time, the fastener elements are wholly concealed from view. However, I contemplate that under other circumstances, this flap may be dispensed with and the fastener elements attached to or formed in the main body of the cuff. Thus for example, when buttons are employed, these buttons may be secured to the shoe upper and the cuff provided with buttonholes. In this case the buttons may be of large and ornamental character if desired thus enhancing the appearance of the cuff.

I wish it to be understood that the invention so far as its broader aspects are concerned is not limited to the specific disposal of or means for supporting the attaching or fastener elements and that the above suggestions as to specific types of such fastener elements are cited merely by way of example.

In the accompanying drawings I have illustrated certain embodiments of my invention by way of example and in the drawings—

Fig. 1 is a side elevation of an overshoe of substantially usual type having an ornamental cuff at its top;

Fig. 2 is a side elevation of my improved overshoe omitting the cuff and showing one type of attaching fastener element mounted upon the upper part of the shoe;

Fig. 3 is a developed view of a cuff adapt-

ed for association with the overshoe of Fig. 2, showing such cuff provided with an attaching flap disclosed in the plane of the cuff proper and with fastener elements at its opposite ends;

Fig. 3^a is a perspective view of a foundation cuff furnished with suitable fastener elements.

Fig. 4 is a vertical section substantially 10 on the line 4—4 of Fig. 1, showing the cuff attached to the upper of the overshoe;

Fig. 5 is a view similar to Fig. 4, but showing the parts detached and juxtaposed;

Fig. 6 is a fragmentary side elevation of 15 the upper part of an overshoe showing a cuff secured thereto by means of buttons passing through a downturned flap on the cuff.

Fig. 7 is a view similar to Fig. 6 but showing 20 the buttons engaging buttonholes formed directly in the cuff proper;

Fig. 8 is a view illustrating the application of hooks and eyes for attaching the cuff; and

25 Fig. 9 is a perspective view illustrating a cuff in the form of a complete ring.

Referring to the drawings the numeral 1 indicates an overshoe of any usual type comprising the upper 2, which is usually of 30 waterproof fabric, and the lower part 3, usually of rubber or rubber coated fabric. This overshoe is, as usual, provided with a front opening which is here shown by way of example, as furnished with a row of fastener elements 4 adapted to be brought into 35 or out of engagement by means of a slider 5 of well known type.

This overshoe is provided with a cuff 6 which may, as above suggested, be of the 40 same material as the upper, or of fur, velvet, ornamental leather, or any other suitable material providing the desired effect. In accordance with the present invention this cuff is detachable and to retain it in desired 45 position I furnish the top portion of the upper 2 of the overshoe with one or more, preferably several, fastener elements. As shown in Fig. 2 these fastener elements are snaps 8 disposed closely adjacent to the 50 top edge 7 of the upper.

In Figs. 3, 4 and 5, I have illustrated a cuff of suitable type for use with the overshoe of Fig. 2. This cuff consists of a strip 6^a of suitable material, waterproof if desired 55 which may be itself of such a character as to furnish the desired surface finish which is comprehensively indicated at 6^b, while on the other hand, this strip 6^a may form merely a support for such outside surface 60 finish, consisting for example, of velvet, fur, enamel, etc., suitably applied to the outer face of the strip 6^a. If desired, I may bend or fold the strip 6^a to provide 65 an attached flap 9 disposed substantially parallel to or at a more or less acute an-

gle to the body portion of the cuff. This flap 9 carries the fastener elements 10 complementary to the elements 8 of the shoe upper, thus permitting the cuff to be attached to the shoe upper in the manner indicated in 70 Fig. 4. While I have shown this attached flap consisting of a fold of the strip 6^a it may, if desired, be formed as a separate strip secured or otherwise attached to the strip 6^a. 75

I may also provide the ends of the band forming the cuff with eyes 11 and hooks 12 or equivalent means for uniting the ends of the band when in use but these fastener elements at the ends of the band may be omitted 80 if desired.

In Fig. 3^a I have shown a cuff foundation consisting merely of a base 13 of suitable material having fastener elements for example ordinary fastener sockets 10^a which 85 are adapted to engage the complementary snaps 8 at the top of the overshoe. This band 13 of foundation material may be sold with the overshoes and is adapted to be covered before use with any fabric or substances suitable for imparting the desired 90 finish or appearance to the outer surface of the cuff. This material may cover the entire outside surface of the foundation strip and if desired overlap the edges of the latter, but on the other hand, it may be preferred to leave uncovered a narrow portion along one edge of the foundation strip to constitute an attaching flap and furthermore, one may also terminate the ornamental or 95 other surface material along a line such as 14 so as to leave a flap 15 of the foundation fabric uncovered and adapted to receive the other surface material along a line such as 100 14 so as to leave a flap 15 of the foundation fabric uncovered and adapted to receive the fastener elements 16 complementary to fastener elements 17 at the other end of the 105 strip or band.

In Fig. 6 I have shown the cuff 6 provided with a flap 9^a similar to the flap 9 as above described and I furnish this flap with buttonholes 21 adapted to receive buttons 110 22 secured to the upper 2. In Fig. 7 I show the cuff 6 unprovided with a flap, but having buttonholes 21^a in the upper part of the cuff proper. These buttonholes receive buttons 22^a secured to the shoe upper and if 115 these buttons be of ornamental character, they may, by proper selection of color or shape be made to enhance the ornamental appearance of the cuff.

In Fig. 8 I have shown the upper 2 of the 120 overshoe provided with an eye 18 of a character such for example as is employed in dressmaking which is adapted to receive a hook 19 secured to the cuff 6. In this view the cuff consists merely of a piece of plush 125 or fur having the foundation of skin portion 20 from which the pile or hair projects.

In Fig. 9 the cuff 6^a is in the form of a complete ring or circle and I show it as furnished with an inner downturned flange 9^a 130

provided with the fastener elements 10. This form of cuff is intended primarily for use with a Russian boot or the like which has no front opening, but might be used 5 with an ordinary overshoe if desired.

As above stated the manufacturer may furnish each pair of overshoes with several pairs of cuffs of different materials or colors, or with several cuff foundations, thus 10 enabling the wearer to select or provide himself with the cuff best harmonizing with his other garments at any particular time. Moreover, such cuffs may be furnished to the dealers independently of the overshoe, 15 and as these cuffs need be made in but few sizes and are relatively cheap as compared with the overshoe as a whole, it is possible for the retail dealer to carry a large assortment of cuffs in stock.

20 While I have shown certain desirable embodiments of the invention I wish it to be understood that the invention is not thus limited but that I contemplate other arrangements and particularly variations in 25 the materials employed and in the proportions of parts as falling within the scope of my invention.

I claim:

1. A waterproof overshoe having an upper, fastener elements attached to the upper 30 near its top edge, and a detachable cuff comprising an elongate strip of material folded longitudinally to provide a relatively narrow attaching flap and a relatively wide body portion, fastener elements secured to 35 the attaching flap, and fastener elements secured to opposite ends of the strip to unite said ends whereby to form a complete circular cuff.

40 2. A waterproof overshoe having an upper, a series of fastener elements extending along the top edge of the upper, an elongate strip of material, said strip having a longitudinal fold forming two plies, one of 45 said plies normally engaging the outer surface of one of the members constituting the top portion of the shoe upper, a series of fastener elements attached to the inner surface of said latter ply, said elements being 50 complementary to those carried by the shoe upper and normally engaging the latter, the other ply depending from the fold line to provide a cuff-like member adapted to embrace the shoe upper.

55 3. A detachable cuff for waterproof overshoes comprising an elongate strip of material, said strip having a longitudinal fold line adjacent to one edge, the broader portion of the strip at one side of the fold

line having a finished surface, and a series 60 of fastener elements extending substantially from one end to the other of the narrower portion of the strip at the opposite side of the fold line, said fastener elements being arranged detachably to engage complementary 65 fastener elements at the outer surface of the top edge portion of the shoe upper.

4. A waterproof overshoe having an upper provided with an opening, a cuff embracing the top of the upper, the ends of 70 the cuff being disposed respectively adjacent to opposite sides of said opening, and the upper edge of the cuff being substantially flush with the top of the upper, said cuff comprising an elongate strip of material 75 having an attaching flap secured to its upper edge, said flap normally engaging the surface of the upper, a series of spaced fastener elements extending substantially from one end of the flap to the other, and a series 80 of complementary fastener elements carried by the upper and normally engaging the elements on the flap whereby detachably to secure the cuff to the upper.

5. A waterproof overshoe comprising an 85 upper having an opening at the front, a cuff embracing the upper, the ends of the cuff being disposed respectively adjacent to opposite sides of the front opening of the upper, said cuff comprising a strip of ornamental material of substantially uniform width 90 and a relatively narrow attaching flap depending from the upper edge of said ornamental strip and disposed at the inner side of the latter, said attaching flap normally 95 engaging the upper, and complementary fastener elements carried by the flap and upper respectively, said fastener elements normally engaging whereby to retain the cuff in position but being readily separable to 100 permit removal of the cuff.

6. A detachable cuff for waterproof overshoes comprising an elongate flexible band having an ornamental outer surface, attaching means united to said band, and a series 105 of fastener elements carried by the attaching means, said band being arranged to extend substantially around the outer surface of one of the members constituting the top portion of the shoe upper, the fastener elements being arranged detachably to engage complementary fastener elements carried by the shoe upper with the line of union of the band, and attaching means substantially 110 flush with the top edge of the upper.

Signed by me at Boston, Massachusetts, this 19th day of January, 1927.

VICTOR B. PHILLIPS.
